CHANNEL EXTENSION IN TELEGRAPH SYSTEMS

Richard E. Mathes, Westfield, N. J., assignor to Radio Corporation of America, a corporation of Delaware

Application November 1, 1938, Serial No. 238,168

18 Claims. (Cl. 178—52)

This invention relates to channel extension in multiplex telegraph systems in which signals are relayed automatically from one station to another through still another station. Such channel extension is desirable in radio circuits because of atmospheric conditions or because of the desire to use the more powerful or more directional system of the station through which the channel is automatically extended. Channel extension is also more economical both in wave bands and in equipment used in the communication system. In wire line telegraphy such extension is often desirable or necessary because of storms, floods or other catastrophes that may interrupt or cripple direct service between two stations, while service between a third station and each of said two stations remains unaffected.

The invention is useful in both radio and wire systems but by way of example, it has been illustrated in connection with radio systems.

An object of the invention is to relay or extend the channel from a branch or controlled station, through the main or control station, to another branch station with minimum change of equipment already installed for direct communication between the stations.

Another object is to maintain in synchronism two mechanically separate channel-selecting means by driving one selecting means by alternating or pulsating current generated by the other selecting means.

Another object of the invention is to drive the transmitting selector or kicker of a station by a synchronous motor obtaining its operating current from an alternating or pulsating, current generator driven by the kicker of the receiver at such station.

Another object of the invention is to automatically delay the phase of the signals received at the channel extending station so that the transmitted pulse can be selected from the approximate center of a baud or basic signal unit.

Other objects will appear in the following description, reference being had to the drawings, in which:

Fig. 1 is a symbolic representation of a main station and two branch stations.

Fig. 2 is a part symbolic and a part circuit arrangement of the receiver and transmitter of a station such as B and C.

Fig. 3 is a part symbolic and part circuit arrangement of a station such as A.

Fig. 4 is a series of graphs showing the character of the signals as they progress through the system.

In multiplex systems, the wire transmission line in wire telegraphy or the radio equipment in radio telegraphy is assigned in rapid succession to a number of keying or receiving channels. The number of channels thus combined may number from two upwards. In radio circuits it has been found that the combining of three channels makes a very satisfactory system and in explaining my invention a three channel system will be assumed, though obviously more or less channels may be used.

Multiplex systems of various numbers of channels are well known in the art, as shown for example, in my Patent No. 1,979,484, of November 6, 1934. Expedients for keeping the receiving distributor in synchronism with the transmitter distributors are also known in the art. For a detailed description of a suitable arrangement I refer to my Patent No. 2,038,375, dated April 21, 1936. Various other well known devices will be necessarily referred to in explaining the operation of my invention. To fully illustrate and completely explain all these well known devices would needlessly expand the disclosure. I therefore will illustrate and describe in detail only such prior art devices and methods as will be necessary to a full understanding of the invention.

In multiplex systems where there is only direct communication between the main or control station and the branch or controlled stations, it is only necessary for the main station to control the speed of the receiving distributors at the branch stations and vice versa, but to successfully carry out automatic channel extension in such system, it is necessary for the control or relay station to control also the speed of the transmitting distributor at the controlled or re-laying stations.

To aid in understanding the problem and therefore applicant's solution in channel extension, let it be assumed that a transmitting station in New York has facilities for communicating with a station in Chicago and another station in San Francisco. It will also be assumed that this New York station will have a transmitter and a receiver for Chicago communication and another transmitter and receiver for San Francisco communication. The Chicago station will likewise have a transmitter and a receiver reserved for the New York station and an additional transmitter and receiver for the San Francisco station. San Francisco will be similarly equipped with a pair of units for New York communication and another pair for Chicago.

communication. With this prior art construction the New York transmitter would cause its Chicago receiver to operate in absolute synchronism or at a constant proportional speed with its own transmitting distributor (Mathes Patent 2,028,375). This would be accomplished by the standard frequency unit and the speed correction unit later described herein. Similarly the Chicago transmitter, reserved for New York communication, would control the speed of the distributor of its receiving station at New York. The transmitters and receivers of the other communication circuits referred to would be similarly tied up. In each case the transmitter controls the distributor speed of its distant receiver. All of the transmitter distributors would operate approximately at the same speed only. This prior art circuit is entirely satisfactory as long as there is no attempt to relay messages through another station by channel extension. It makes no difference to New York in direct communication that its Chicago receiving distributor is out of step with its Chicago transmitter. If atmospheric or other conditions makes it inadvisable to communicate, say from Chicago to San Francisco, and there is good communication conditions between Chicago and New York, and between New York and San Francisco, Chicago will relay its San Francisco communication through the New York station. Under such conditions it is absolutely necessary that the New York receiver, reserved for Chicago communication, be running in synchronism or at a constant proportional speed in respect to the transmitter at New York which is to relay the communication on to San Francisco.

It is also necessary at the relay station, New York in the example given, to adjust the phase of the communication coming in from Chicago so that it will fit in with the other channels that are sending communications to San Francisco through the same distributor.

There has been an attempt to overcome the foregoing disadvantage so that communication can be automatically relayed from one station to another in multiplex systems, but as far as I am aware, in such systems this has been done by mounting the receiving and transmitting distributors on a common shaft. While this secures the desired control, it greatly reduces the flexibility of the system and in addition requires major and expensive mechanical and electrical changes to be made in existing systems where the distributors are separate and sometimes widely separated from each other. Another disadvantage of such a channel extension system is that the inbound system fails whenever the outbound system fails. In such case this shuts down not only the relaying system but also the direct station-to-station communication. In my invention these difficulties are overcome.

In Fig. 1, I have shown a channel extension system in more or less symbolic form to illustrate the general operation of my improvement. The main or control station A located, for example, at New York city, has a transmitter 1 and receiver 2 for direct communication with the the receiver 3 and transmitter 4 of a branch station B located at Chicago, for example. The main station A, also has a transmitter 5 and a receiver 6 for communicating with the receiver 7 and transmitter 8 of branch station C located, for example, at San Francisco. This is illustrative only, as various other branch stations in this or foreign countries could have similar con-

nections with the main station and any of the branch stations could be equipped for extending their channels through the main station.

Fig. 2 illustrates in considerably more detail the apparatus used in the stations. At the branch stations it is essential that the transmitting distributor 9 and the receiving distributor 10 run at synchronism for channel extension. To accomplish this, I install on the driving shaft of the receiving distributor a toothed wheel 11 of magnetic material so as to rotate in unison therewith. Adjacent to the periphery of this toothed wheel is a solenoid 12 having preferably an iron core with a small air gap between such core and the teeth of the wheel. This solenoid may be energized by any suitable source such as the battery 13 and it may be connected to an amplifier 14 to produce the desired output. The distributor shaft of the receiver is run by a synchronous motor 15 taking its driving current from a Thyratron inverter power-unit 16 whose frequency is set by the standard frequency unit 17 either at the frequency of the standard or any sub-multiple thereof. This standard frequency unit may be of the well known type controlled by a tuning fork and having temperature regulation to maintain a standard frequency to within one part in 100,000 over a long period of time. Such a constant frequency unit is described in an article written by me jointly with J. L. Callahan and A. Kahn, in the Proceedings of the Institute of Radio Engineers, January, 1938, volume 26, No. 1, page 71. The standard frequency units at the branch stations B and C are exactly the same as the standard frequency unit of transmitting station A.

Inverter power units are well known, being fully described in the literature, for example, on pages 231 to 242, inclusive, of a book entitled "Electron Tubes in Industry," by Keith Henney, published by McGraw Hill Book Company, 1937 edition. The application of inverter power-units to facsimile telegraph systems is also disclosed in the patent to C. J. Young, No. 2,117,587, May 17, 1938. It therefore will be unnecessary to describe the details of the inverter unit 16 herein. It will be sufficient to say that the standard frequency unit 17 maintains an alternating or pulsating current of substantially constant frequency and low power, and this is applied to the grid of the gas tubes of the inverter to maintain a source of voltage of the same frequency or any harmonic or sub-harmonic thereof, at any desired higher power. The gas tubes are frequently called "Thyratrons" or "Grid glow" tubes.

Since the voltage of the inverter unit 16 is applied to the synchronous motors 15, the distributor shaft and the toothed wheel 11 will run synchronously with the frequency of the inverter which has either the frequency of the standard frequency unit or any selected multiple or sub-multiple thereof, depending upon its adjustment. Also, since the same standard frequency unit is being operated at the control station A, all the motors 15 will run in practical synchronism with the desired frequency unit of the main or control station. However, it is practically impossible to construct two standard frequency units such as 17 that will run in absolute synchronism over a long period of time. As a practical matter there will always be a very slight difference even in the best designed units and to correct for this inescapable, though minute difference in

the frequencies of the standard units; the speeds of the distributor shafts at the branch stations are corrected to absolute synchronism by the correction unit 18 and a correction motor 19 geared to the frame, or stator, as it is usually called, of the synchronous motor 15.

The standard frequency units, distributors and other parts referred to herein of course need not be run at one and the same speed. The units 10 and devices may operate at different frequency or speed and the principle of the invention may be used so long as such frequencies or speeds bear a constant ratio to each other.

In general, the speed is corrected to maintain 15 absolute synchronism between the distributor shaft of the receiver of a branch station with the distributor of the transmitter at the control station by means of the signals themselves. These signals, of course, are in absolute synchronism at all times with the transmitter sending 20 out such signals though there may be, and in nearly all cases is, a slight shift in phase. This speed correction unit is well known in the art, being described in my above mentioned Patent No. 2,038,375.

It may be said, however, that in this speed control system the distributors of the receivers are run by synchronous motors that are energized by alternating current generators (gas tube 30 inverters being disclosed), controlled by the standard frequency units. Standard frequency units are tuning-fork controlled and they are set so that they operate at frequencies to within one part in 100,000 of each other. This minute difference in frequency would soon throw the transmitter and receiver distributors out of step and to keep them absolutely in synchronism, or at speeds bearing a constant ratio to each other, a pulsating current is generated by the dot and 40 dash signals arriving at the receiver from the distant transmitter. A portion of the signal energy arriving at the receiver is passed through a transformer which generates a pulse at the beginning and also at the end of each dot or dash. 45 One of these is suppressed, say, the terminal pulse, and the other one is used to energize a relay to place voltage of one polarity on a field of a motor that rotates the stator of the synchronous motor in one direction when the receiving distributor is operating fast. This pulse when 50 the distributor is running slow energizes the relay to apply voltage of opposite polarity, to the speed correction motor which kicks the stator of the synchronous motor in the opposite direction. 55 As long as the receiving distributor is operating in step with the transmitting distributor the circuit to the pulse generating transformer is open, being controlled by contacts on the distributor. No claim is made herein to this speed control 60 feature, per se, as it is disclosed and claimed in Mathes Patent No. 2,038,375, referred to herein.

With the speed control equipment referred to, it will be seen that the toothed wheel 11 in the branch stations will be rotated synchronously 65 with the distributors 20 of the transmitters at the main station A. Though it may also be run by gearing, or otherwise, to produce a sub-multiple or harmonic frequency since the desired frequency for the transmitter distributor can be 70 obtained by adjustment of the inverter. If the standard frequency units 17 are maintaining substantially a frequency of 480 cycles per second, and the synchronous motors 15 are connected to operate on the eighth sub-harmonic, or 60 cycles, from the output of the inverters 16, then

the speed correction unit will run the motor frame of the synchronous motor 15 at the branch stations B and C either forwards or backwards to increase or decrease the speed to maintain the distributors 9 and 10 in absolute synchronism with the distributor 20 of the control station A.

The distributors 21 and 22 of the two receiving stations at control station A are likewise run by synchronous motors 15 supplied with power from 10 the local inverter power units 16 whose frequency is set by the standard frequency unit 17 of station A. The speed of each of these distributors at station A is likewise corrected by speed correction motor 19 to maintain the distributors in synchronism with the transmitter distributor of station B or station C and in constant phase relation therewith. The distributors 9 of the transmitters when no channel extension is made are operated by inverters 27, already described, such inverters having their frequency set by the standard frequency unit, switches 23 being then closed on contacts 24. If the standard frequency units at stations B and C should be slightly out of synchronism with standard frequency unit 17 of station A, the speed correction units 18 at station A will maintain the receiving distributors 21 and 22 in synchronism with the transmitter shaft at stations B and C.

The speed controls as already described are ample for taking care of direct communication between stations A and B, and between stations A and C. However, as will be appreciated, the speed correction units do not maintain the receiving distributors 21 and 22 at station A in absolute synchronism with the transmitting distributor shafts 20 at station A. The speeds of these receiving distributors at station A will differ from the speed of the transmitting distributors at the same station by the amount that the standard frequency units 17 at station B or C depart from the frequency of unit 17 at station A. Thus, with the regular equipment already described, it would be impracticable to 45 relay communication from one branch station to the other branch stations through the control station A.

By throwing switches 23 at the branch stations so as to engage contacts 25, the solenoid 50 12 is able to control the frequency applied to the synchronous motors 26 operating the distributors 9. If it be assumed that the inverters are so adjusted that all stations are operating on the eighth sub-multiple of the standard 480 55 frequency of the units 17, or 60 cycles, and that the toothed wheels 11 at stations B and C have 16 teeth, there will be generated in the solenoids 12 a frequency of 480 cycles, the synchronous motors 15 having four poles. If a standard frequency unit 17 at station A varies a light amount from 480 cycles per second, the frequency produced by the tone wheel 11 and solenoid 12 will vary exactly by the same amount because the speed correction unit 19 is maintaining the distributor shaft in exact synchronism with the frequency unit at station A. The inverter power units 27 thus produce a frequency in exact synchronism or a sub-multiple or harmonic frequency with the standard frequency unit 17 at station A but they may have a slight phase delay in comparison with the standard frequency units 17 at stations B and C.

Since the inverter power units 27 by assumption are adjusted to work on the eighth sub-

multiple of 480 cycles the synchronous motor 26 and the transmitting distributors 9 at stations B and C will be operated on 60 cycles and will be in synchronism with the transmitting distributors 20 at station A though not necessarily in exact phase.

With this explanation, let it be assumed that station B is communicating with station C on channel I by relaying such communication through station A, and that channels II and III of stations A and C and A and B are being used in direct communication.

Referring particularly to Fig. 2 for more detailed explanation of stations C and B, the messages in channels I, II and III will be sent out by telegraphic tape transmitter heads. These heads are run by synchronous motors 31 fed with alternating current from inverter 27 at the desired frequency. They, therefore, are run synchronously with the transmitter distributor arm 39. These heads are well known in the art and need not be described further than to say that perforated tape is fed through the heads by the mechanism and at the beginning of each dot or dash, the switch members 32 are thrown into engagement with the positive terminal of some source such as the battery 33. At the close of each dot or dash the switches are thrown into engagement with the negative terminal of the battery 33.

The signal that is to be relayed through station A to station C by assumption will be sent through channel I but the progress of all three signals will be traced from station B to station A. The impulses sent out by the keyers will go over transmission lines 34 to the contacts on the distributor. The signals being sent out by extended channel I and direct channels II and III are given at Ia, IIa and IIIa in Fig. 4. These three graphs give the full dots, dashes and spaces of the Morse code in a portion of the message. When the distributor arm engages contact 35 a pulse of current 40 (graph Ib, Fig. 4) will pass from channel I through contact 35, distributor arm 39, to collector brush 41 and to the grid of vacuum tube 42 of the locking circuit tone keyer. Toothed clutches 40 between the synchronous motors and the transmitting heads permit one to adjust these heads in respect to the position of the arm 39 and thus assure that the contacts will be made at the center of each baud. The current through brush 41 continues to flow only so long as the distributor arm is in engagement with contact 35. In practice this pulse of current 40 will be much less than the length of a baud depending upon the width of the contacts, the width of the brush and the spacing between the contacts. A pulse of about $\frac{1}{10}$ to $\frac{1}{30}$ of a baud will be found suitable.

The pulse of current reaching the grid of tube 42 applies a positive potential thereto which sends current through resistance 43 to the negative terminal of the battery. Before this pulse was applied the locking unit was in unstable condition because of the interconnection of the grids to the plate circuits as explained in the patent of J. L. Finch, No. 1,844,950, February 16, 1932.

Before the pulse was applied to the grid of tube 42 current from the positive terminal of the locking unit came in through connection 44 where it divided and passed in two different branches, one being through resistance 45, resistance 46, resistance 47, to the negative terminal. The current in the other branch passed

through resistance 48, resistance 49 and resistance 43, to the negative terminal. The drop in these various resistances might place both grids just above the cut-off point or just below it, depending upon the chosen values of the resistances. In either case this is an unstable arrangement and either one tube or the other is certain to take slightly more plate current, for example, tube 51, and this will draw increased current from the positive terminal 44 through resistance 48 to the plate and filament 50 of the tube and to ground which is connected to the intermediate terminal of the battery. This decreases the potential at the junction point 52 and correspondingly lowers the potential at junction point 53. Since this latter junction point is connected to the grid of tube 42, this grid goes more negative and the tube draws less current. This decreases the load current through resistance 45 and raises the potential of junction point 54 by decreasing the drop in resistance 45 and this lowers further still the potential on the grid of tube 42 due to increased current in the plate circuit of tube 51. The net result is that the tubes in the locking arrangement, when no signal pulse is being received, are so unstable that either one tube or the other is always drawing current and the other one is blocking.

By assumption, tube 51 is drawing current and tube 42 is blocking at the time that the positive pulse 40 (graph Ib of Fig. 4) is applied to the grid of tube 42. The positive pulse 40 applied at the junction point 53 raises the potential of the grid of tube 42 and it starts drawing current. Because of the cross connection of the grids this will cause tube 51 to instantly block. When contact arm 39 leaves contact 35, pulse 40 terminates. Nevertheless, current still continues to flow through the tube 42 because of the locking arrangement already explained. A positive potential is applied through the conductor 55 to the grid of push pull tube 56 in the tone keyer arrangement. This causes push pull tubes 56 and 57 to draw current in push pull fashion and current will continue to flow from the time pulse 40 was applied to the grid until the balance of the locking arrangement is upset. Tone generator 58 therefore will send a tone modulated current through transformer 59 and transmission line 60 to the transmitter 61 and radiation will commence.

When the contact arm 39 engages contact 36 of channel II, positive pulse 62 (graph IIb) will be applied to the grid at point 53. This itself would have been sufficient to cause tube 42 to draw current, but since it is already drawing current by means of the locking arrangement it has no effect. The contact arm 39 next engages contact 37 and sends out positive pulse 63 (graph IIIb) from channel III. This likewise has no effect on tube 42 as it is already drawing current.

When the contact arm again swings on to contact 35, positive pulse 64 will be sent out from extended channel I. This likewise will cause no change in the locking circuit. When the contact arm reaches contact 36, negative pulse 65 (graph IIb) will be sent out because, as will be shown by graph IIa, a space is reached at this time. The head sends out negative pulses for all spaces. A negative pulse is then applied to junction point 53. This lowers the potential of the grid so that the tube 42 blocks and tube 51 instantly draws current through the unsta-

ble equilibrium produced by the cross connection of the grids. This causes a negative potential to be applied to the grid of push pull tubes 56 and 57. These tubes then block and no signal is sent out by transmitter 61. This terminates the composite signal character 66 (graph V).

When the contact arm reaches contact 37 negative pulse 66 from channel III will be produced but this has no effect as tube 42 is already blocked. When the contact arm reaches contact 35 a positive potential is still being applied to channel I, as shown by graph Ia. A positive pulse 67 is therefore applied to junction point 53. This instantly causes tube 42 to draw current and tube 51 to block. This terminates the composite space character 68 (graph V) of the composite signal being sent out by the transmitter 61.

The point at which transmitting channels I, II and III are connected by contacts 35, 36 and 37 to the locking unit can be readily determined by inspection of the group I of graphs in Fig. 4. The positions of channels I, II and III at the top of this group indicate the moment that contact is made between the distributor arm and each of the three contacts. The vertical lines proceeding from these Roman numerals indicate whether a positive or a negative pulse is transmitted to the grid of tube 42. To determine this one has merely to note where the lines from I, II and III cross the graphs Ib, IIb and IIIb, respectively.

It will be seen without further detailed description that the distributor arm and locking arrangement will combine the signals into a composite arrangement shown by graphs IV, V, which will be unintelligible to an unauthorized listener. Graph IV is the composite signal reaching the tone keyers and graph V is the composite signal radiated by the antenna.

At the receiving station A, Figs. 1 and 3, the signals will be received on the antenna of receiver 2 and will be fed into the distributor 21. The signal received will take the form shown in graph VI of Fig. 4. This will be the same as graph V. In the graphs of group B the receiving signals are shown. The Roman numerals at the top of this group show the times of closure of the contacts on the receiving distributor of station A. As will be noted, these contacts are closed a half baud later than the closure at the transmitter distributor station C because of the desire to have these closures made at the center of the bauds of graph VII.

The received signal will be tone-keyed, amplified and rectified, after which it will appear as a pulsating current, as shown by graph VII. The locking unit 70 of the receiving apparatus at station A is like the one described in connection with the transmission from station B but since rectified current, in which the potentials change from positive to zero and vice versa, is applied to the locking unit instead of alternating current, in which the potentials change from positive to zero and vice versa. I use a coupling tube 71 before the signal reaches the locking unit and a condenser 72 between the distributor unit and the locking unit 70. Battery 73 biases the grid of tube 71 positive so that it normally conducts current through resistance 74.

When contact 75 engages contact 76, point 66 under Roman numeral I thereabove of graph VII shows that a positive potential exists at double rectifier 77 across ground terminal 78 and center tap 79, the terminal 78 being positive and

the center tap 79 being negative. This biases the grid of tube 71 so strongly negative that it blocks. There being no plate current through resistance 74, practically the full voltage of the battery is applied through contact 76 to the 5 condenser 72 and grid resistance 80. Resistance 80 is high in comparison to resistance 74 so that the charging or displacement current of condenser 72 produces a sufficient positive drop around the former to cause the tube 81 to draw 10 current and tube 82 to block. Channels II and III would have a locking unit and condenser connected to contacts 83 and 84, respectively, but the operation will be understood with only one locking arrangement being shown. 15

When the tube 81 began to draw current, current started to flow from conductor 85 through resistance 86 to the plate of the tube and thence to the filament and to ground. Since tube 82 is blocked no plate current flows through resistance 87. The phasing delay device 88 is connected across resistance 86 and 87 by conductors 89 and 90. When tube 81 is drawing current conductor 90 is positive and conductor 89 negative. When tube 81 blocks and tube 82 draws current, 25 the polarity of conductors 89 and 90 is reversed. Before explaining the phasing or delay action the reformation of the signals of all three channels will be traced.

When tube 81 draws current dash 91 (graph 30 Ic) starts to form and this dash will continue due to the action of the locking unit until a much diminished potential is placed on the grid of tube 81. By inspection of graph VII it will be clear that there is no change in potential 35 except between points 92 and 93. This cannot affect locking tube 81, however, because the distributor arm 75 is not in engagement with contact 76 of channel I during the space between points 92 and 93, as will be clear by referring 40 to the Roman numerals at the top of Fig. 4.

The next change in potential occurs between the points 94 and 95 of graph VII. By referring to the Roman numerals at the top of Fig. 4, it will be seen that contact 75 engages contact 76 of channel I at the point 94'. Consequently, the dash in channel I (graph Ic) terminates at 96 and the space 97 starts to form. When point 94' was reached in the composite signal the rectifier 79 produced no current. This 50 meant that the negative bias was removed from the grid of tube 71 and it drew current due to the positive bias of battery 73. This produced a drop in load resistance 74 of tube 71 and the voltage applied to condenser 72 was decreased 55 by the amount of the drop therein. Condenser 72 therefore discharged and placed a momentary bias on the grid of tube 81 due to the drop in resistance 80 produced by the discharge current. This discharge took place through the 60 distributor arm to the plate of tube 71 and thence to the filament and to the negative terminal of the battery through ground and thence through resistance 80 to the other side of condenser 72. 65

The negative charge on the grid of the tube 81 caused the tube to instantly block and tube 82 to draw current. This caused current from the positive terminal to flow through conductor 85 and resistance 87 and thence through the 70 plate-filament circuit of tube 82. This flow of current produced a drop in resistance 87 that made conductor 90 negative and conductor 89 positive. This reversal of current acted on the phasing delay unit but before describing that 75

action all of the signals will be traced through the distributor.

The space 97 continues until there is another change of potential applied to condenser 72. On inspection of graph VII in connection with the vertical lines connected to the Roman numerals at the top of the graphs of group B, Fig. 3, it will be seen that channel I cannot be affected until the point 98 is reached. At 10 no place between points 94 and 98 of this graph is contact arm 75 in engagement with contact 76 of channel I. However, at point 98, arm 75 does make engagement with contact 76 and the grid of tube 81 grows strongly positive due to 15 the action of the rectifier 77 and coupling tube 78 already explained. The dash of channel I thus commences to form at the point 98' and it cannot be interrupted until there is an interruption of the current at the time that arm 20 75 reaches contact 76. By an inspection of graph VII it is seen that the first interruption of the current is between points 99 and 100. By tracing the vertical lines from these points to the Roman numerals at the top of the graphs 25 of group R, it will be seen that channel I is not affected at this time. Therefore, the dash starting at 98' continues until point 102 is reached on the composite signal shown in graph VII. By following the vertical line from point 30 102 to the top of the group of graphs it is seen that channel I is affected because arm 75 is in engagement with contact 76. No current, therefore, flows at this time through rectifier 77 to place a negative bias on tube 78. Condenser 72 therefore discharges again and places 35 a negative bias on the grid of tube 81 and the tube instantly blocks. This reverses the polarity of conductors 89 and 90 again and the dash begun at point 98' of graph Ic ends at 102. By 40 referring to graph Ia of group I of Fig. 4 of the original signal in channel I, it will be seen that graph Ic is exactly the same as graph Ia except that it has been relayed one full baud in time due to the fact that the signal was delayed a half baud by being picked off in the 45 middle of the baud at the transmitter and again a half baud at the receiver for the same reason.

Channels II and III would be connected to a condenser and locking arrangement like those 50 of channel I in Fig. 2. In channel II the signal starts to form at point 103 of graph IIc. By inspection of the composite signals shown in graph VII, it will be seen that there is no change of potential until the point 92 is reached and 55 by following the vertical line upwards to the top of Fig. 4 it is at once seen that this is applied to contact 83 of channel II at the point 104. This terminates the character at point 104 in graph IIc and a space then starts to 60 form which continues until the next change of potential affecting channel II occurs. By inspection of graph VII it is seen that this change of potential does not occur until point 105 of the composite signal is reached. The vertical 65 line through this point shows that channel II is affected and the space terminates at 106 (graph IIc). Another signal character then starts to form. This will continue until there is another change of potential affecting channel II. It will be seen from an inspection of graph VII that the potential does not change until point 99 is reached in that graph. Here the potential drops one-half baud before contacts 75 and 83 are in engagement. The signal 70 channel in channel II therefore terminates at 75

107 (graph IIc). This starts the formation of a space and the space will continue until there is a change in potential while contact 75 engages contact 83. This does not occur until point 103 of graph VII is reached. At this time 5 a new character starts at point 109 (graph IIc). This continues until the potential is again changed while arm 75 is in engagement with contact 83. This does not happen until point 110 is reached in graph VI. The signal character, therefore, ends at point 111.

By comparing the graph IIc, group R, with the original of graph Ia, group T, it will be seen that they are exactly the same but the signal starts later by two bauds. 15

In channel III the signal character starts forming at 112. At point 113 of graph VII, switch arm 75 is in engagement with contact 84. Since at this time graph VII shows that no current is flowing, the signal character will 20 terminate at 114. The space will continue until the potential changes. At point 116 the arm and contact of channel III are together again and at this point there is a potential increase so another signal in channel III will start at 25 116. This continues until the next engagement of the contacts which occurs at 117 (graph VII). Since the potential drops at this point the signal in graph IIIc terminates at 118. A space then starts to form. The contacts of channel 30 III are next in engagement at point 119 of graph VII. Since there is current flowing at this point a new signal in graph IIIc starts at 120. The contacts in channel III are next in engagement at 35 121. At this time positive potential also exists. Therefore, the signal character continues without change. At point 122 the contacts of channel III are again in engagement. At this time graph VI shows that positive potential exists. Therefore, the signal character started at 40 120 of graph IIIc still continues. The contacts are next in engagement at point 123. Graph VII shows that at this time no current is flowing and therefore the signal character in channel 45 IIIc ends at 124. By comparing reconstructed signals of channel III in IIIc with the original signals of this channel in graph IIIa, it will be be seen that the two are identical except that the former has been delayed in phase one and one-half bauds. 50

Since receiving channels II and III, by assumption, terminated at station A, there is nothing further to explain in connection with these two channels except to say that they would be connected to locking circuits similar to 70 55 and to recording or other receiving devices which are well known in the art and are not shown. Channel I, however, by assumption, is to be relayed at station A, to station C. Therefore, the signal of graph Ic will be traced further. 60

As previously explained, and as shown in Fig. 3, this signal has been placed by the conductors 99 and 90 on the phase delay unit 88 so that adjustment can be made to provide for the taking of the signal at approximately the center part 65 of the baud.

Phase delay expedients are well known in the art. Combinations of resistance and capacity as well as resistance and inductance will provide for easy shift of phase. Also magnetic storing 70 devices for shifting the phase may be used and I have shown the latter type merely by way of example.

The magnetic phase delay is essentially like the well known telephone where a signal is 75

stored on magnetic material, except for phase shift variation, as in my invention, the pick-up should be adjustable. In the device shown in Fig. 3 a disc 125 of magnetic material of suitable magnetic permanency is rotated by any constant speed motor 126. This may be a clockwork mechanism or any type of electric motor adapted to maintain a constant speed.

Magnet 127 places a magnetic bias on the disc 125, one side being a north pole and the other side a south pole. Electromagnet 128 superimposes a magnetization from the signals on this disc and pick-up magnet 129 has a variable current generated by the variable magnetization placed on the disc by magnet 128. The pick-up magnet 129 is adjustable around the disc, towards or from the magnet 128, as indicated by the double arrow 130. Magnet 127 then wipes off the magnetization placed on the disc by the electromagnet 128 and restores the magnetic bias.

When the signals received over channel I reverse the polarity of conductors 89 and 90, as already explained, the polarity of magnet 128 25 reverses and it places a corresponding magnetization on the disc 125. As the disc rotates this magnetization produces a pulse of current in the pick-up magnet 129. By adjusting the pick-up magnet 129 towards or from magnet 128 the 30 phase of the signal pulses in magnet 129 can be readily adjusted in respect to the signal currents in magnet 128. By the magnetic phase shifter the phase can be delayed so that the distributor arm of the transmitter 20 at station A can pick 35 off the signals at the center of a baud. This can be readily done by a stroboscope such as neon lamp 132 connected by brushes and lines 134 with the potentiometer 135 that carries the signal currents. The lamp 132 and the perforated disc 40 136 rotate in synchronism with the transmitting distributor 20 and the flashing of the light through the perforation 137 will give the position of the signal characters in respect to the contact 133. This stroboscopic indicator is not 45 part of my invention and it need not be further described since it is known in the art and its operation will be obvious.

After passing through the phase shifter the signals are preferably sent again through a locking circuit 138 like the transmitter locking circuit of Fig. 2 so that they will have a square form more suitable for combining with the local signals in transmitter channels II and III which likewise come through similar locking circuits 55 (not indicated). After passing through the distributor 20, the composite signals pass into the locking circuits and tone keyer 139 like those of Fig. 2, and thence to the transmitting apparatus 140.

60 The radiated signal is received at station C and regenerated as already explained in connection with station A and this need not again be explained.

It will be clear that additional channels of 65 station C can likewise be extended to station B by way of station A. This can be taken care of by appropriate switches, not shown.

It will be apparent that signals can be extended through two or more relaying stations 70 to another station instead of only one as I have described by way of example. Also, it will be clear that the main station need not be the relaying station when the other stations are equipped with my improvement. If station B is 75 communicating directly with station C then sta-

tion B can use one or more channels to relay its communication through station C to still another station. This can be done since station A is controlling the speed of the receiver distributors at all stations and the generator distributors are being run in synchronism with or proportional to the speed of the receiving distributors.

Obviously my improvement may be used in two-way multiplex telegraphy between two stations 10 through the same relaying station and the speed of the distributors in communicating in one direction may be the same as, or different from, the speed of the distributors in the other direction.

Instead of the toothed wheel and solenoid, I may use any other type of synchronous generator for fixing the speed of the distributors at the branch stations so that the channels may be extended through the controlling station A. Also, 20 the generators need not be secured directly on the shaft of the distributors as they may be geared or otherwise connected to generate currents of synchronous frequency or proportional frequency such as sub-multiples of the synchronous frequency.

Various phase shifting or delaying devices may be used in the place of the one illustrated. For example, I may use the one described in the application of Alfred Kahn, filed Nov. 1, 1938, Serial 30 No. 238,167, assigned to the assignee of my application.

While I have shown a particular form of connecting means for maintaining the distributors of the various branch or controlled stations in synchronism with the distributor of the main or control station, it must be understood that other kinds of connecting means may be used. Also various other changes may be made in the system described without departing from the spirit 40 of the invention.

Having described my invention, what I claim is:

1. In a multiplex telegraph system, a telegraph station having a transmitter and a receiver, means for connecting a plurality of receiving channels in succession to the receiver, a generator operated by said means for producing alternating potentials of a frequency proportional to the rate of connection of said channels and means for connecting a plurality of transmitting channels to the transmitter under the control of said alternating potentials and at a rate proportional to the frequency thereof.

2. In a multiplex telegraph system, a telegraph station having a transmitter and a receiver, a distributor for each transmitter and receiver, means for running the receiver distributor, at a predetermined speed, a generator of alternating potentials operated by the receiving distributor to run at a proportionate speed, and means electrically connected to said generator for running said transmitter distributor at a speed proportional to the frequency of said alternating potentials.

3. In a multiplex telegraph system, a telegraph station having a transmitter and a receiver, distributors for the transmitter and the receiver, means for running the receiving distributor at a predetermined constant speed, a generator of alternating potentials operated by the receiving distributor to run at a speed proportional to the speed thereof, a synchronous motor for running the transmitting distributor and

electrically connected to said generator to run at a speed proportional thereto.

4. In a multiplex telegraph system, two stations each having a transmitter and a receiver, channel connecting distributors for the transmitters and the receivers of each station, means for running the receiver distributor of one station at a predetermined speed, a generator of alternating potentials operated by the receiving distributor of said one station to run at a speed proportional thereto, a synchronous motor connected to run the transmitting distributors of said one station, and means at the other of said stations for adjusting the phase of the signals received from said one station.

5. In a multiplex telegraph system, a control station and a controlled station, each having a transmitter and a receiver, connections for a plurality of signal channels for the transmitter and for the receiver of said stations, means for connecting the transmitter of the control station to each of its channels in continuous succession at a constant rate, means for connecting the receiver of the controlled station to each of its respective channels in continuous succession at a rate in synchronism with the rate of connection at the control transmitter, an alternating current generator driven with the connecting means for the receiver of the controlled station at a speed proportional to the frequency of said rate of connection, and means for connecting the transmitter of the controlled station to each of its respective channels in continuous succession, said last mentioned means being driven by a synchronous motor operated under synchronous control from the said generator.

6. In a multiplex telegraph system, a control station and a controlled station, each of said stations having a transmitter and a receiver, a plurality of signal channels for the transmitter and for the receiver of said station, means for connecting the transmitter of the control station to each of its channels in continuous succession at a constant rate, means for connecting the receiver of the controlled station to each of its respective channels in continuous succession at a rate in synchronism with the rate of connection at the control transmitter and in phase therewith, an alternating current generator having a frequency proportional to the rate of connection of the receiver of the controlled station, means for connecting the transmitter of the controlled station to each of its respective channels in succession, said last mentioned means being operated from the generator of its receiver at a frequency proportional to the frequency of the generator, and means for connecting the receiver at the control station to each of its respective channels in succession and in synchronism with the connecting means of the transmitter of the controlled station.

7. In a multiplex system having a control station and a plurality of controlled stations, each of said stations having a transmitter and a receiver, a plurality of signal channels for the transmitter and for the receiver of each station, means for connecting the transmitter of the control station to each of its respective channels in continuous timed succession at the same and substantially constant rate, means for connecting the receiver of each controlled station to each of its respective channels in continuous succession at a rate in substantial synchronism with the rate of connection of the connecting means of the control transmitters and in phase therewith,

an alternating current generator driven with the connecting means for the receiver of each controlled station at a frequency proportional to the rate of connection, means for connecting the transmitter of each controlled station to each of its respective channels in succession, said last mentioned means being operated from the generator of its respective receiver at a frequency proportional to the frequency of the generator, means for connecting the receiver at the control station to each of its respective channels in succession in synchronism with the connecting means of the last mentioned transmitter and means in circuit with at least one of the last mentioned channels to delay for a desired interval of time the transference of signal characters therethrough.

8. A multiplex telegraph system having a control station and a plurality of controlled stations, each of said controlled stations having a transmitter and a receiver and said control station having separate transmitters and receivers for communication with each controlled station, a plurality of signal channels for the transmitter and for the receiver of each station, means for connecting the transmitters of the control station to each of their respective channels in continuous succession at the same and substantially constant rate, means for connecting the receiver of each controlled station to each of its respective channels in continuous succession at a rate in substantial synchronism with the rate of connection of the connecting means of the control transmitters, and in phase therewith an alternating current generator driven with the connecting means for the receiver of one of the controlled stations and having a frequency proportional to its rate of connection, a synchronous motor for connecting the transmitter of each controlled station to each of its respective channels in succession, said last mentioned means being operated from the generator of its receiver and at a frequency proportional thereto, means for connecting one of the receivers at the control station to each of its respective channels in succession and in synchronism with the connecting means of the transmitter of one of the controlled stations, at least one of the last mentioned channels having an electrical connection with the channels of one of the transmitters of the control station, and a phase delay device in said electrical connection.

9. In a multiplex telegraph system, a control station having a transmitter, a controlled station having a transmitter and a receiver, channel-connecting distributors for said transmitters and receiver, means for operating the distributor for said control station and the distributor for said receiver at speeds bearing a constant ratio to each other and means electrically operated by the receiving distributor for driving the transmitting distributor of said controlled station at a speed bearing a constant ratio to the speed of said receiving distributor.

10. In a multiplex telegraph system, two stations each having a transmitter and a receiver, a plurality of message-channels for each transmitter, a distributor for connecting the message-channels of each transmitter in succession thereto, a plurality of message-channels for each receiver, a distributor for connecting the message-channels of each receiver in succession thereto, means for operating the distributor of a transmitter of each station and that of a receiver of the other station at speeds bearing a constant

- ratio to each other, and means electrically operated by the distributor of the receiver of one station for driving the distributor of the transmitter of that station at a speed bearing a constant ratio thereto.

11. In a multiplex telegraph system, two transmitters and two receivers, a plurality of message channels for each transmitter and for each receiver, a distributor for each transmitter and each receiver for connecting its message-channels in succession thereto, means for operating the distributor of one transmitter and the distributor of one receiver at speeds bearing a constant ratio to each other, means for operating the distributor of the other transmitter and the other receiver at speeds bearing a constant ratio to each other, means operated by the distributor of one receiver for producing a pulsating voltage and a motor operated from said voltage for driving the distributor of one of said transmitters at a speed bearing a constant ratio thereto.

12. In a multiplex telegraph system, two stations each having a transmitter and a receiver, a plurality of message-channels for each transmitter, a distributor for connecting the message-channels of each transmitter in succession thereto, a plurality of message-channels for each receiver, a distributor for connecting the message-channels of each receiver in succession thereto, means for operating the distributor of a transmitter of each station and that of the receiver of the other station at speeds bearing a constant ratio to each other, means electrically operated by the distributor of the receiver of one station for driving the distributor of the transmitter of that station at a speed bearing a constant ratio thereto and means to adjust the phase of the signals arriving from the last mentioned transmitter to coincide with that of the distributor of the other transmitter.

13. In a multiplex telegraph system, two transmitters and two receivers, a plurality of message-channels for each transmitter and for each receiver, a distributor for each transmitter and each receiver for connecting its message-channels in succession thereto, means for operating the distributor of one transmitter and one receiver at speeds bearing a constant ratio to each other, means for operating the distributor of the other transmitter and the other receiver at speeds bearing a constant ratio to each other, means operated by the distributor of one receiver for producing a pulsating voltage, a motor operated from said voltage for driving the distributor of one of said transmitters at a speed bearing a constant ratio thereto, and means to adjust the phase of the signals arriving at one receiver from one transmitter to coincide with that of the distributor of the other transmitter.

14. In a multiplex telegraph system, a control station having a transmitter, a controlled station having a transmitter and a receiver, channel-connecting distributors for said transmitters and receiver, means for operating the distributor for said control station and the distributor for said receiver at speeds bearing a constant ratio to each other, a generator of alternating current operated by the receiving distributor and a synchronous motor energized by said generator for driving the distributor of the transmitter of the controlled station.

15. In a multiplex telegraph system, two stations each having a transmitter and a receiver, a plurality of message-channels for each transmitter, a distributor for connecting the message-channels of each transmitter in succession thereto, a plurality of message-channels for each receiver, a distributor for connecting the message-channels of each receiver in succession thereto, means for operating the distributor of a receiver of each station and the transmitter of the other stations at speeds bearing a constant ratio to each other, a generator of alternating current operated by the distributor of the receiver of one station and a synchronous motor energized by said generator for driving the distributor of the transmitter of that station.

16. In a multiplex telegraph system, two transmitters and two receivers, a plurality of message-channels for each transmitter and for each receiver, a distributor for each transmitter and each receiver for connecting its message-channels in succession thereto, means for operating the distributor of one transmitter and one receiver at speeds bearing a constant ratio to each other, means for operating the distributor of the other transmitter and the other receiver at speeds bearing a constant ratio to each other, a generator of alternating current operated by the distributor of one receiver and a synchronous motor energized by said generator for driving the distributor of one of said transmitters.

17. In a multiplex telegraph system, two transmitters and two receivers, a plurality of message-channels for each transmitter and for each receiver, a distributor for each transmitter and each receiver for connecting its message-channels in succession thereto, means for operating the distributor of one transmitter and one receiver at speeds bearing a constant ratio to each other, means for operating the distributor of the other transmitter and the other receiver at speeds bearing a constant ratio to each other, a generator of alternating current operated by the distributor of one receiver, a synchronous motor energized by said generator for driving the distributor of one of said transmitters and means to adjust the phase of the signals arriving from one transmitter to coincide with that of the distributor of the other transmitter.

18. In a multiplex telegraph system, two stations each having a transmitter and a receiver, a plurality of message-channels for each transmitter, a distributor for connecting the message-channels of each transmitter in succession thereto, a plurality of message-channels for each receiver, a distributor for connecting the message-channels of each receiver in succession thereto, means for operating the distributors of a transmitter of each station and the receiver of the other station at speeds bearing a constant ratio to each other, a generator of alternating current operated by the distributor of the receiver of one station, a synchronous motor energized by said generator for driving the distributor of the transmitter of that station and means to adjust the phase of the signals arriving from the last mentioned transmitter to coincide with that of the distributor of the other transmitter.
